(57) **CLAIM**

The ornamental design for a door for a laundry appliance, as shown and described.

DESCRIPTION

FIG. 1 is a first perspective view of a door for a laundry appliance showing our new design; and

FIG. 2 is a front view thereof; and,

FIG. 3 is a second perspective view thereof.

The broken line showing of an interior region of the door is for environmental purposes only and forms no part of the claimed design.

1 Claim, 3 Drawing Sheets**FIG. 1**

FIG. 2

FIG. 3
